UNITED STATES PATENT OFFICE.

WILLIAM WILDE, OF URBANA, ILLINOIS.

COMBINED TIE AND RAIL-FASTENER.

1,018,538.

Specification of Letters Patent. Patented Feb. 27, 1912.

Application filed September 11, 1911. Serial No. 643,690.

To all whom it may concern:

Be it known that I, WILLIAM WILDE, a citizen of the United States, residing at Urbana, in the county of Champaign and 5 State of Illinois, have invented a new and useful Combined Tie and Rail-Fastener; and I do hereby declare the following to be a full, clear, and exact description of the invention, such as will enable others skilled 10 in the art to which it appertains to make and use the same.

This invention relates to a new and useful combined tie and rail fastener.

The principal object of the invention is 15 the provision of a novel form of rail fastener, in which there is involved simplicity and practicability.

A feature of the invention is the provision 20 of a member counter sunken in a tie having angular plates slidable into position, for locking the rail in place.

The invention comprises further features and combination of parts, as hereinafter set forth, shown in the drawings and claimed.

25 In the drawings:—Figure 1 is a view in perspective, of a rail tie, showing the application of the improved fastener as applied thereto, the same being constructed in accordance with the invention. Fig. 2 is a 30 longitudinal sectional view. Fig. 3 is a detail view of one of the fasteners, removed from the member which is embedded in the tie. Fig. 4 is a detail view of one of the members 3 and one of the rail clamping 35 plates 14, showing the same ready to be received by the member 3.

Referring more especially to the drawings 1 designates a suitable tie, which may be constructed of wood, cement or any other 40 suitable material. This tie, at each end is provided with a recess or depression 2, of considerable depth. Arranged in the recesses or depressions 2 are members 3, which consist of head portions 4, base portions 5 45 and the web connecting parts 6. The head portions 4 are centrally recessed as shown at 7 for the reception of the base flanges 8 of the rails 9. On each side of the recesses 7, the head portions are provided with 50 trough like gutters or guides 10, the upper openings 11 of which are restricted, as shown. The bottoms of the trough like gutters or guides are provided with recesses

12, which form the shoulder 13. Arranged in the trough like gutters or guides are the 55 rail clamping plates 14, the rear ends 15 of which abut against the shoulders 13, for holding the plates in contact with the rails. The tongue portions 16 of the rail clamping plates are of a width to snugly fit the restricted openings 11 of the trough like gutters or guides, while the bodies 17 of the rail clamping plates are just wide enough to fit closely between the walls 18 of the trough like gutters or guides. The shoulders 19 of the rail clamping plates engage the under surfaces of the overhanging flanges 20 of the trough like guides, so as to prevent upper displacement of the plates. 60

In securing the rails in position, the rails 70 are first arranged in the recesses 7, after which the body portions of the rail clamping plates are slid through the trough like guides or gutters, with the tongues 16 passing through the restricted openings 11, until the tongues engage the upper surfaces 75 of the base flanges of the rails, then the ends 15 of the bodies 17 are thrown in contact with the shoulders 13 of the recesses 12. By this arrangement the rails are held in 80 position in the recesses 7 securely. Subsequently the members 3 are then dropped or embedded in the recesses or depressions 2 of the tie 1.

The invention having been set forth, what 85 is claimed as new and useful is:

1. In combination, a tie, a member embedded therein and provided with a transverse recess, a rail arranged in the recess, the member having trough like gutters, the 90 trough like guides having recesses, one end of each recess of the guides constituting a shoulder, and rail clamping plates arranged in the guides and partly seated in the recesses thereof with the ends of the plates 95 in contact with the shoulders.

2. In combination, a tie, a member embedded therein and provided with a transverse recess, a rail arranged in the recess, the member having trough like gutters, the 100 trough like guides having recesses, one end of each recess of the guides constituting a shoulder, the guides having restricted upper openings, and rail clamping plates arranged in the guides, the rail clamping 105 plates comprising body portions having re-

stricted tongues to extend through the restricted openings to engage the upper surfaces of the base flanges of the rail, the body portions of the plates being seated in the recesses of the guides with their ends in contact with the shoulders to lock the plates in place.

In testimony whereof I have signed my name to this specification in the presence of two subscribing witnesses.

WILLIAM WILDE.
